PERMUTATION LOCK

Ivan Poderžaj, Hampstead, London, England

Application January 13, 1933, Serial No. 651,588
In Germany September 14, 1932

15 Claims. (Cl. 70—53)

I have filed an application in Germany on September 14, 1932, an application in Great Britain on November 25, 1932 and in France on December 5, 1932.

5 This invention relates to a permutation lock especially adapted for use on house doors or case locks or padlocks, and which may be operated when its permutation mechanism is adjusted in a predetermined combination which may be 10 changed whenever desired.

The invention has for its object to provide a novel type and arrangement of the several adjustable members of said mechanism which are to be adjusted into proper relation by one familiar 15 with the combination. A further object of my invention is to afford facilities for the proper adjustment of the registrable means independently of the spindle in respect to the lock bolt and to relieve said registrable means of each stress 20 executed by said spindle actuating the lock bolt.

A further object is to provide a cheap and a narrow shaped construction of the permutation mechanism which needs not to be placed on a spindle into a narrow lock housing of usual shape.

25 Embodiments of my invention are shown as examples in the accompanying drawing, and these embodiments will be hereinafter more fully described with reference thereto, and the particular features of the invention will be pointed out in 30 the claims at the end of this specification.

Fig. 1 is a front elevation of a permutation lock embodying this invention.

Fig. 2 is an axial section of the lock shown in Fig. 1, in the closed position.

35 Fig. 3 is a similar view with the parts of the lock in an intermediate position.

Fig. 4 is a cross-section on the line II—II of Fig. 2.

40 Fig. 5 is a cross-section on the line III—III of Fig. 2.

Fig. 6 is a cross-section on the line IV—IV of Fig. 2,

Fig. 7 is a front elevation of a detail,

Fig. 8 is a front elevation,

45 Fig. 9 an axial section of guarding means,

Fig. 10 is a side elevation of a bolt,

Fig. 11 is a cross-section through an embodiment of the invention shaped as a padlock, and

50 Fig. 12 shows a fragmentary section of a detail of the construction represented in Fig. 5.

In the front plate of the lock housing 1 there is rotatably and axially displaceably mounted a ring or hollow cylinder 2, the displacement of which is limited by a stop 3 fixed thereon. The 55 hollow cylinder 2 is provided with a projection 4

and serves, by means of this, as the driving member of the lock bolt 6, which is displaceably mounted on a projection 7 of the casing 1. The projection 4, by the displacement of the cylinder 2, is brought into engagement with a nose piece 5 of the bolt 6, which is actuated by a spring 8 tending to hold the bolt in the closed position. The opening of the bolt takes place by rotating the cylinder 2 in the direction of the arrow (Fig. 1) after the cylinder 2 has been moved to such an extent that the projection 4 engages into the path of the nose piece 5 (Fig. 3). The cylinder 2 is provided with a locking device comprising a group of rotatable sleeves 9 concentrically arranged for the purpose of being rotated in a predetermined particular permutation position enabling said group of sleeves to be shifted longitudinally. In the example shown, there are five such sleeves arranged one within the other which are rotatable but not axially displaceable 20 with respect to each other. On the external sleeve 9 is arranged the cylinder 2, adapted to rotate but not to move longitudinally thereon. The cylinder 2 is provided with a guide pin 10 which engages in a groove 11. The sleeves 9 engage together in a similar way by guide pins 12 and grooves 13.

The sleeves 9 (Fig. 5) are provided on their external circumferential surfaces with grooves 14 and on their inner surfaces with spring teeth 15. The grooves 14 serve as rests to the springs 15 which snap into said grooves on the rotation of the sleeves to secure their position with respect to each other. On the front end of the cylinder 2 is arranged an annular scale 16, the divisions of which are indicated by numbers or letters. On the front ends of the sleeves 9 are fixed 30 pointers 17, by which the sleeves can be rotated and adjusted to particular divisions of the scale.

On the rear ends of the sleeves 9 are fixed pins 18 arranged parallel to the axis of the sleeves and disposed opposite a locking plate composed of rings and fixed to the rear wall of the lock housing 1. The rings 19 are each provided, on the face opposite to the sleeve, with a hole 20. The holes 20 are capable of receiving the pins 18 when the latter are directed co-axially with the holes in the rings as shown in Fig. 2, for example. The position of the pins shown in Fig. 2 therefore coincides with the combination position of the holes 20, which permits the displacement of the sleeves 9 into the working position. In this operative position the driving projection 4 engages in the path of the nose piece 5 of the 55

bolt in such a manner that the bolt can be opened by rotating the cylinder 2.

The combination position of the holes 20 can be changed by adjustment of the counter rings 19 which are held in the corresponding position by a blocking member 21. This member consists of a ring fixed on a shoulder 23 of the lock housing and having arms 22 which engage in grooves 24 of the rings 19 for blocking the same.

10 A loop 26 is rotatably fitted at 25 on the cylinder 2 and serves as a handle in the rotation of the cylinder 2.

To prevent unauthorized adjustment of the counter rings 19, there is fitted over the blocking ring 21 a guarding member or cap 27 which is screwed on a shaft 28 provided with threads and mounted to be rotatable and axially movable in an axial hole 29 of the innermost ring 19. The shaft 28 is loosely arranged in a central hole 30 of the sleeves and provided with a lug 31. The innermost sleeve is provided with a slot 32 which engages in said lug when the sleeves are shifted into the operative position shown in Fig. 3. When the sleeves are adjusted in their predetermined position, the cap 27 can be screwed off the shaft 28, and the blocking member may be displaced for the adjustment of the rings 19 into a different position. As shown by Figs. 8 and 9, the threaded hole of the cap is closed at the outside by a fixed wall 35, thereby preventing the danger of retaining improperly the terminal of the shaft 28 and of unpermitted unscrewing of the cap 27 as well as of finding out the combination position.

In order to counteract the weight of the pins 18, and thereby make it more difficult to detect the position of the pins the sleeves 9 are preferably provided with insets of heavy metal arranged diametrically opposite to the pins 18, and which act as counter-balance. In the example shown in Fig. 7, each of the sleeves 9 is provided with an auxiliary pin 18' serving as counter-balance and displaced by about 190° (instead of 180°) with respect to the pin 18 in order not to have to reduce the number of permutation positions. Holes 20' in the locking plate 19 (Fig. 4) correspond to the pins 18', which engage therein when the pins 18 are introduced into the holes 20 in the locking plate.

The plate 19 comprises stationary rings having at their frontal surface depressions 33. When unauthorized persons make tapering attempts in order to find the effective position of the pins 18 and shift the rings 9, the depressions 33 receive the free terminal ends of the pins 18, so as to permit only incomplete and inactive shifting motions of the pins 18.

The lock can be used for purposes of any kind, for example as a door lock according to Fig. 4, or a padlock according to Fig. 11, or as a locking device in which the bolt is closed positively, or by spring pressure.

The working of the lock is as follows. The position of the zero point of the movable rings 9 is selected in accordance with the position of the rings of the plate 19 and may be indicated upon the casing 1 by means of a vertical line corresponding to the vertical diameter of the rings 19. The zero line of the scale 16 is designated by the numeral "0" and its direction is congruent to the direction of the vertical line enclosing the zero point of the ring system 19. For the purpose of unlocking the rings 19 are turned, till their pointers 17 are adjusted opposite the numerals or letters of the scale which are selected to correspond to the operative posi-

tion of the pins of the movable rings. The sleeves are then locked in the operative position in which the projection 4 of the cylinder is in the path of the nose piece 5 of the bolt 6 which can now be moved against the pressure of the spring 8 by rotating the cylinder 2 by hand actuating the handle 26, in order to open the lock. When the handle 26 is released, the bolt is closed by the spring 8. The group of sleeves 9 is then drawn out of engagement with the rings 19 until the pins 18 are out of engagement, whereupon the sleeves 9 can be brought into disorder.

Having now particularly described and ascertained the nature of my said invention and in what manner the same is to be performed, I declare what I claim is:—

1. In a permutation lock, a casing having a pair of spaced walls, a cylinder rotatably and slidably mounted in one of said walls, a series of concentric sleeves nested in the casing and independently rotatable with respect to the cylinder and each other, a locking plate supported by the opposite wall and consisting of a series of mutually rotatable rings each of equal diameter to a respective sleeve, pins projecting from the sleeves toward said locking plate, each ring of the locking plate having a hole therein to receive the pin of the corresponding sleeve, pointers on the outer ends of said sleeves, a scale on the cylinder over which said pointers traverse, means to rotate the cylinder, and means to secure the rings in selected position.

2. In a permutation lock, a casing having a pair of spaced walls, a cylinder rotatably and slidably mounted in one of said walls, a series of concentric sleeves nested in the casing and independently rotatable with respect to the cylinder and each other, a locking plate supported by the opposite wall and consisting of a series of mutually rotatable rings each of equal diameter to a respective sleeve, pins projecting from the sleeves toward said locking plate, each ring of the locking plate having a hole therein to receive the pin of the corresponding sleeve, pointers on the outer ends of said sleeves, a scale on the cylinder over which said pointers traverse, means to rotate the cylinder, said rings having their outer ends grooved radially, a blocking member having arms engaging the grooves of the rings, and means to secure the blocking member in place.

3. In a permutation lock, a casing having a pair of spaced walls, a cylinder rotatably and slidably mounted in one of said walls, a series of concentric sleeves nested in the casing and independently rotatable with respect to the cylinder and each other, a locking plate supported by the opposite wall and consisting of a series of mutually rotatable rings each of equal diameter to a respective sleeve, pins projecting from the sleeves toward said locking plate, each ring of the locking plate having a hole therein to receive the pin of the corresponding sleeve, pointers on the outer ends of said sleeves, a scale on the cylinder over which said pointers traverse, means to rotate the cylinder, said rings having their outer ends grooved radially, a blocking member having arms engaging the grooves of the rings, means to secure the blocking member in place, and a detachable cover extending over the blocking member and outer ends of the rings.

4. In a permutation lock, a casing having a pair of spaced walls, a cylinder rotatably and slidably mounted in one of said walls, a series of concentric sleeves nested in the casing and independently rotatable with respect to the cylinder

and each other, a locking plate supported by the opposite wall and consisting of a series of mutually rotatable rings each of equal diameter to a respective sleeve, pins projecting from the sleeves 5 toward said locking plate, each ring of the locking plate having a hole therein to receive the pin of the corresponding sleeve, pointers on the outer ends of said sleeves, a scale on the cylinder over which said pointers traverse, means to rotate the cylinder, said rings having their outer ends grooved radially, a blocking member having arms engaging the grooves of the rings, means to secure the blocking member in place, a bolt slidably 10 in said casing transverse the axis of the sleeves, and coacting means on the bolt and inner end of the cylinder engaging when the cylinder is moved inwardly to effect movement of the bolt upon rotation of the cylinder.

10. In a permutation lock, a casing having a pair of spaced walls, a cylinder rotatably and slidably mounted in one of said walls, a series of concentric sleeves nested in the casing and independently rotatable with respect to the cylinder and each other, a locking plate supported by the opposite wall and consisting of a series of 15 mutually rotatable rings each of equal diameter to a respective sleeve, pins projecting from the sleeves toward said locking plate, each ring of the locking plate having a hole therein to receive the pin of the corresponding sleeve, pointers 20 on the outer ends of said sleeves, a scale on the cylinder over which said pointers traverse, means to rotate the cylinder, said rings having their outer ends grooved radially, a blocking member having arms engaging the grooves of the rings, 25 means to secure the blocking member in place, a detachable cover extending over the blocking member and outer ends of the rings, a bolt slidably in said casing transverse the axis of the sleeves, and coacting means on the bolt and inner 30 end of the cylinder engaging when the cylinder is moved inwardly to effect movement of the bolt upon rotation of the cylinder.

5. In a permutation lock, a casing having a pair of spaced walls, a cylinder rotatably and slidably mounted in one of said walls, a series of concentric sleeves nested in the casing and independently rotatable with respect to the cylinder and each other, a locking plate supported by the opposite wall and consisting of a series of 25 mutually rotatable rings each of equal diameter to a respective sleeve, pins projecting from the sleeves toward said locking plate, each ring of the locking plate having a hole therein to receive the pin of the corresponding sleeve, pointers 30 on the outer ends of said sleeves, a scale on the cylinder over which said pointers traverse, means to rotate the cylinder, said rings having their outer ends grooved radially, a blocking member having arms engaging the grooves of the rings, 35 means to secure the blocking member in place, a detachable cover extending over the blocking member and outer ends of the rings, a shaft extending rotatably through said locking plate and into the innermost sleeve, said cover being 40 screwed on the outer end of said shaft and normally rotatable therewith, and coacting means on the inner sleeve and inner end of the shaft for holding said shaft from rotation in the sleeve when the latter is moved inwardly.

45. 6. In a permutation lock, a casing having a pair of spaced walls, a cylinder rotatably and slidably mounted in one of said walls, a series of concentric sleeves nested in the casing and independently rotatable with respect to the cylinder and each other, a locking plate supported by the opposite wall and consisting of a series of 50 mutually rotatable rings each of equal diameter to a respective sleeve, pins projecting from the sleeves toward said locking plate, each ring of the locking plate having a hole therein to receive the pin of the corresponding sleeve, pointers on the outer ends of said sleeves, a scale on the cylinder over which said pointers traverse, means to rotate the cylinder, said rings having their outer ends grooved radially, a blocking member having arms engaging the grooves of the rings, 55 means to secure the blocking member in place, a detachable cover extending over the blocking member and outer ends of the rings, means controlled by the longitudinal movement of the cylinder and sleeves for controlling release of the cover, a bolt slidably in said casing transverse the axis of the sleeves, and coacting means on the bolt and inner end of the cylinder engaging when the cylinder is moved inwardly to effect movement of the bolt upon rotation of the cylinder.

60. 7. In a permutation lock, a casing having a pair of spaced walls, a cylinder rotatably and slidably mounted in one of said walls, a series of concentric sleeves nested in the casing and independently rotatable with respect to the cylinder and each other, a locking plate supported by the opposite wall and consisting of a series of 65 mutually rotatable rings each of equal diameter to a respective sleeve, pins projecting from the sleeves toward said locking plate, each ring of

the locking plate having a hole therein to receive the pin of the corresponding sleeve, pointers on the outer ends of said sleeves, a scale on the cylinder over which said pointers traverse, means to rotate the cylinder, said rings having their outer ends grooved radially, a blocking member having arms engaging the grooves of the rings, means to secure the blocking member in place, a bolt slidably in said casing transverse the axis of the sleeves, and coacting means on the bolt and inner end of the cylinder engaging when the cylinder is moved inwardly to effect movement of the bolt upon rotation of the cylinder.

8. In a permutation lock, a casing having a pair of spaced walls, a cylinder rotatably and slidably mounted in one of said walls, a series of concentric sleeves nested in the casing and independently rotatable with respect to the cylinder and each other, a locking plate supported by the opposite wall and consisting of a series of 20 mutually rotatable rings each of equal diameter to a respective sleeve, pins projecting from the sleeves toward said locking plate, each ring of the locking plate having a hole therein to receive the pin of the corresponding sleeve, pointers 25 on the outer ends of said sleeves, a scale on the cylinder over which said pointers traverse, means to rotate the cylinder, said rings having their outer ends grooved radially, a blocking member having arms engaging the grooves of the rings, 30 means to secure the blocking member in place, a detachable cover extending over the blocking member and outer ends of the rings, a bolt slidably in said casing transverse the axis of the sleeves, and coacting means on the bolt and inner 35 end of the cylinder engaging when the cylinder is moved inwardly to effect movement of the bolt upon rotation of the cylinder.

9. In a permutation lock, a casing having a pair of spaced walls, a cylinder rotatably and slidably mounted in one of said walls, a series of concentric sleeves nested in the casing and independently rotatable with respect to the cylinder and each other, a locking plate supported by the opposite wall and consisting of a series of 40 mutually rotatable rings each of equal diameter to a respective sleeve, pins projecting from the sleeves toward said locking plate, each ring of the locking plate having a hole therein to receive the pin of the corresponding sleeve, pointers on the outer ends of said sleeves, a scale on the cylinder over which said pointers traverse, means to rotate the cylinder, said rings having their outer ends grooved radially, a blocking member having arms engaging the grooves of the rings, 45 means to secure the blocking member in place, a detachable cover extending over the blocking member and outer ends of the rings, means controlled by the longitudinal movement of the cylinder and sleeves for controlling release of the cover, a bolt slidably in said casing transverse the axis of the sleeves, and coacting means on the bolt and inner end of the cylinder engaging when the cylinder is moved inwardly to effect movement of the bolt upon rotation of the cylinder.

10. In a permutation lock, a casing having a pair of spaced walls, a cylinder rotatably and slidably mounted in one of said walls, a series of concentric sleeves nested in the casing and independently rotatable with respect to the cylinder and each other, a locking plate supported by the opposite wall and consisting of a series of 50 mutually rotatable rings each of equal diameter to a respective sleeve, pins projecting from the sleeves toward said locking plate, each ring of

- the locking plate having a hole therein to receive the pin of the corresponding sleeve, pointers on the outer ends of said sleeves, a scale on the cylinder over which said pointers traverse, means to rotate the cylinder, said rings having their outer ends grooved radially, a blocking member having arms engaging the grooves of the rings, means to secure the blocking member in place, a detachable cover extending over the blocking member and outer ends of the rings, a shaft extending rotatably through said locking plate and into the innermost sleeve, said cover being screwed on the outer end of said shaft and normally rotatable therewith, coacting means on the inner sleeve and inner end of the shaft for holding said shaft from rotation in the sleeve when the latter is moved inwardly, a bolt slideable in said casing transverse the axis of the sleeves, and coacting means on the bolt and inner end of the cylinder engaging when the cylinder is moved inwardly to effect movement of the bolt upon rotation of the cylinder.
11. In a permutation lock, a casing having a pair of spaced walls, a cylinder rotatably and slidably mounted in one of said walls, a series of concentric sleeves nested in the casing and independently rotatable with respect to the cylinder and each other, a locking plate supported by the opposite wall and consisting of a series of mutually rotatable rings each of equal diameter to a respective sleeve, pins projecting from the sleeves toward said locking plate, each ring of the locking plate having a hole therein to receive the pin of the corresponding sleeve, pointers on the outer ends of said sleeves, a scale on the cylinder over which said pointers traverse, means to rotate the cylinder, means to secure the rings in selected position, a bolt slideable in said casing transverse the axis of the sleeves, and coacting means on the bolt and inner end of the cylinder engaging when the cylinder is moved inwardly to effect movement of the bolt upon rotation of the cylinder, and spring pawls each carried by one of said cylinders and engaging the adjacent cylinder, said cylinders being provided with peripheral series of ratchet notches in which said pawls engage.
12. In a permutation lock, a casing having a pair of spaced walls, a cylinder rotatably and slidably mounted in one of said walls, a series of concentric sleeves nested in the casing and independently rotatable with respect to the cylinder and each other, a locking plate supported by the opposite wall and consisting of a series of mutually rotatable rings each of equal diameter to a respective sleeve, pins projecting from the sleeves toward said locking plate, each ring of the locking plate having a hole therein to receive the pin of the corresponding sleeve, pointers on the outer ends of said sleeves, a scale on the cylinder over which said pointers traverse, means to rotate the cylinder, said rings having their outer ends grooved radially, a blocking member having arms engaging the grooves of the rings, means to secure the blocking member in place, a bolt slideable in said casing transverse the axis of the sleeves, coacting means on the bolt and inner end of the cylinder engaging when the cylinder is moved inwardly to effect movement of the bolt upon rotation of the cylinder, and spring pawls each carried by one of said cylinders and engaging the adjacent cylinder, said cylinders being provided with peripheral series of ratchet notches in which said pawls engage.
13. In a permutation lock, a casing having a pair of spaced walls, a cylinder rotatably and slidably mounted in one of said walls, a series of concentric sleeves nested in the casing and independently rotatable with respect to the cylinder and each other, a locking plate supported by the opposite wall and consisting of a series of mutually rotatable rings each of equal diameter to a respective sleeve, pins projecting from the sleeves toward said locking plate, each ring of the locking plate having a hole therein to receive the pin of the corresponding sleeve, pointers on the outer ends of said sleeves, a scale on the cylinder over which said pointers traverse, means to rotate the cylinder, said rings having their outer ends grooved radially, a blocking member having arms engaging the grooves of the rings, means to secure the blocking member in place, a detachable cover extending over the blocking member and outer ends of the rings, a bolt slideable in said casing transverse the axis of the sleeves, coacting means on the bolt and inner end of the cylinder engaging when the cylinder is moved inwardly to effect movement of the bolt upon rotation of the cylinder, and spring pawls each carried by one of said cylinders and engaging the adjacent cylinder, said cylinders being provided with peripheral series of ratchet notches in which said pawls engage.
14. In a permutation lock, a casing having a pair of spaced walls, a cylinder rotatably and slidably mounted in one of said walls, a series of concentric sleeves nested in the casing and independently rotatable with respect to the cylinder and each other, a locking plate supported by the opposite wall and consisting of a series of mutually rotatable rings each of equal diameter to a respective sleeve, pins projecting from the sleeves toward said locking plate, each ring of the locking plate having a hole therein to receive the pin of the corresponding sleeve, pointers on the outer ends of said sleeves, a scale on the cylinder over which said pointers traverse, means to rotate the cylinder, said rings having their outer ends grooved radially, a blocking member having arms engaging the grooves of the rings, means to secure the blocking member in place, a detachable cover extending over the blocking member and outer ends of the rings, means controlled by the longitudinal movement of the cylinder and sleeves for controlling release of the cover, a bolt slideable in said casing transverse the axis of the sleeves, coacting means on the bolt and inner end of the cylinder engaging when the cylinder is moved inwardly to effect movement of the bolt upon rotation of the cylinder, and spring pawls each carried by one of said cylinders and engaging the adjacent cylinder, said cylinders being provided with peripheral series of ratchet notches in which said pawls engage.
15. In a permutation lock, a casing having a pair of spaced walls, a cylinder rotatably and slidably mounted in one of said walls, a series of concentric sleeves nested in the casing and independently rotatable with respect to the cylinder and each other, a locking plate supported by the opposite wall and consisting of a series of mutually rotatable rings each of equal diameter to a respective sleeve, pins projecting from the sleeves toward said locking plate, each ring of the locking plate having a hole therein to receive the pin of the corresponding sleeve, pointers on the outer ends of said sleeves, a scale on the cylinder over which said pointers traverse,

means to rotate the cylinder, said rings having their outer ends grooved radially, a blocking member having arms engaging the grooves of the rings, means to secure the blocking member in place, a detachable cover extending over the blocking member and outer ends of the rings, a shaft extending rotatably through said locking plate and into the innermost sleeve, said cover being screwed on the outer end of said shaft and normally rotatable therewith, coacting means on the inner sleeve and inner end of the shaft for holding said shaft from rotation in the sleeve

when the latter is moved inwardly, a bolt slideable in said casing transverse the axis of the sleeves, coacting means on the bolt and inner end of the cylinder engaging when the cylinder is moved inwardly to effect movement of the bolt upon rotation of the cylinder, and spring pawls each carried by one of said cylinders and engaging the adjacent cylinder, said cylinders being provided with peripheral series of ratchet notches in which said pawls engage.
